UNITED STATES PATENT OFFICE.

CHARLES RIDLEY LUMLEY, OF NEWCASTLE, WASHINGTON.

DESIGN FOR A CASING FOR A TRAFFIC SIGNAL.

Application filed June 23, 1924. Serial No. 9,953. Term of patent 14 years.

To all whom it may concern:

Be it known that I, CHARLES RIDLEY LUMLEY, a citizen of the United States, and a resident of Newcastle, in the county of King and State of Washington, have invented a new, original, and ornamental Design for Casings for Traffic Signals, of which the following is a specification, reference being had to the accompanying drawing, forming part thereof.

The figure is a perspective view of a casing for a traffic signal, showing my new design.

I claim:

The ornamental design for a casing for a traffic signal, as shown.

CHARLES RIDLEY LUMLEY.
